UNITED STATES PATENT OFFICE.

ALBRECHT LUECK, OF NEW YORK, N. Y.

AIRSHIP.

1,116,715.

Specification of Letters Patent. Patented Nov. 10, 1914.

Application filed February 17, 1914. Serial No. 319,268.

To all whom it may concern:

Be it known that I, ALBRECHT LUECK, a citizen of the German Empire, and resident of New York, in the State of New York, have invented certain new and useful Improvements in Airships, of which the following is a specification.

The object of this invention is to provide a dirigible air-ship specially adapted for use in war. For this purpose the machine is provided with an observation-platform located above the gas-bags, and with a magazine for ammunition, bombs, etc., at the lower part of the machine.

In the accompanying drawing, Figure 1 is a side-view of an air-ship embodying the invention, and Fig. 2 is a top-view of the same.

Similar reference numerals indicate corresponding parts in both figures.

Two gas-bags 10 and 11 respectively are provided, one at each side of the longitudinal center-line of the machine. These bags are spaced apart, and at the inner side of the bag 10 is a vertical plane 12, and at the inner side of the bag 11 a vertical plane 13. The planes are brought together at the bow of the machine, as shown in Fig. 2. At the rear of the machine a crossbar 14 connects the planes, and on said bar is hinged a rudder 15 for steering the machine horizontally, and at each side thereof rudders 16, 17 for steering the same vertically. The rudder 15 is connected by suitable ropes 18 with steering mechanism 19, from which extend also ropes 20 and 21 to vertical rudders 22 and 23 arranged one beneath each gas-bag. The vertical rudders 16 and 17 are connected by suitable ropes 24 with the steering mechanism 19, and ropes 25 connect the steering mechanism with a rudder 26 for steering the bow of the device vertically, said rudder being located at the front part of the machine forward of the gas-bags.

The framework 30 of the machine supports, below the space between the bags, a suitable inclosed platform 31, the rear-portion of which serves as a magazine for containing ammunition such as bombs and other implements of destruction suitable for use in warfare. The motors 32 of the machine are located on the platform, and by means of chains 33 drive the propellers 34, 35, 36, 37, two propellers being located beneath each gas-bag, each propeller in longitudinal alinement with the other beneath

the same bag. The framework 30 supports above the bags a transverse observation-platform or bridge 38 extending completely across the machine and at each end beyond the sides of the bags, as indicated in Fig. 2. On this platform may be stationed a lookout for the purpose of observing the country and the movements of the enemy. The framework 30 also supports, below the plane of the gas-bags, three pontoons 40, 41, 42, each of which is pointed at its forward-end. The outer pontoons 40 and 42 are arranged beyond the vertical plane of the gas-bags respectively and are of smaller size than the central pontoon; the latter is of greater width and approximately the same length as the platform 31, and is of greater width than the space between the gas-bags, and affords direct support to the platform and the heavy ammunition and machinery thereon when the air-ship descends to the sea and rides thereon, the platform 31 forming the top of and resting directly upon the pontoon 41.

For discharging rapidly the bombs or other explosives carried, a bucket-chain 44 is provided suitably mounted on a wheel at the rear-portion of the magazine and connected with the motors 32 or any other suitable source of power which may be carried, so as to be rotated, and thereby deliver the bombs over the rear-end of the platform 31, whence they fall.

For retarding the speed of the air-ship before striking the sea when descending, a bucket 45 is provided having perforations 46 on its bottom, which bucket may be lowered by a rope 47 from the platform, and, by reaching the water-surface before the air-ship has arrived at the same, serves to retard the speed of the air-ship immediately before it enters the water.

Between the vertical planes 12, 13 and the cross-bar 14 at the rear-end of the machine are located, one at each side of the machine, horizontal fixed planes 50, 51 which serve to steady and guide and support the rear-portion of the machine. The bags taken together present a lenticular form, as seen in the figures, whereby they are adapted to act not merely as gas-bags, but to a certain extent as planes for the support of the machine when moving at a rapid rate of speed. The vertical planes 12 and 13 taper gradually from the extreme vertical depth of the bags to a comparatively small depth, as

shown at 55 in Fig. 1, at the stern of the machine, and likewise taper to a comparatively small depth at the bow, as seen at 56, the intermediate vertical plane surface supported, however, being sufficient for maintaining the ready dirigibility of the machine.

The air-ship described provides a convenient and satisfactory means of carrying considerable quantities of high explosives, and of navigating the air and sea for purposes of warfare.

I claim:

1. An air-ship, comprising a gas-field of lenticular form in two bags spaced apart transversely of the machine, vertical planes at the inner face of each bag tapering therefrom toward the bow and stern, vertical and horizontal rudders at the rear of said planes, 20 vertical rudders at the bow, horizontal rudders one beneath each gas-bag, a magazine-platform below the plane of the bags and vertically below the space between the same, propellers beneath each gas-bag, and 25 pontoons, one at each side of the machine beyond the gas-bag and a middle pontoon below the platform.

2. An air-ship, comprising a gas-field of horizontal lenticular form in two bags spaced apart transversely of the machine, 30 vertical planes at the inner face of each bag tapering therefrom toward the bow and stern, vertical and horizontal rudders at the rear of said planes, vertical rudders at the bow, horizontal rudders one beneath each 35 gas bag, horizontal planes at the rear end of the vertical planes, a magazine-platform below the plane of the bags and vertically below the space between the same, propellers beneath each gas-bag, pontoons, one 40 at each side of the machine beyond the gas-bag and a middle pontoon below the platform, and an observation-bridge extending transversely of the machine above the gas-bags and laterally beyond the same over the 45 pontoons.

In testimony, that I claim the foregoing as my invention, I have signed my name in presence of two subscribing witnesses.

ALBRECHT LUECK.
